UNITED STATES PATENT OFFICE

2,269,191

CONTROL SWITCH

John Eaton, Schenectady, N. Y., assignor to General Electric Company, a corporation of New York

Original application July 27, 1940, Serial No. 347,994. Divided and this application July 17, 1941, Serial No. 402,753

3 Claims. (Cl. 200—6)

This application is a division of my application Serial No. 347,994, filed July 27, 1940, for Condition control system and apparatus.

The present invention relates to control switches, particularly multiple contact control switch mechanism adapted for use in the automatic control of condition changing apparatus involving a predetermined sequence of control conditions, or in other similar service.

The improved control switch structure of the present invention is of particular advantage in an automatic oil burner sequence control system such as disclosed and claimed in my above application, although it may be used with advantage in other multiple contact sequence switch service if desired.

The principal object of the invention is to provide an improved complementary nested switch construction wherein the several switch conducting, insulating and supporting parts are specially formed with non-circular bosses and cooperating non-circular openings so as to enable them to be built up and clamped in interlocked nesting relation in such a way that each conducting switch part is insulated from the other conducting switch parts as well as from the supporting parts.

Another object is an improved composite multiple row switch construction particularly adapted for use in a cam operated sequence switch.

The improved complementary switch construction of the present invention enables a multiplicity of switch contact parts and a multiplicity of switch insulating parts, all of substantially duplicate form, to be integrated into a multiple contact switch structure with a common supporting and fastening means for all of the switch parts.

Briefly, in accordance with the invention, each switch comprises an insulating member, preferably of moulded material, provided with non-circular bosses or extensions adjacent its opposite ends, together with a pair of cooperating switch parts, each of which is provided with a non-circular opening so that it may be slid over a corresponding boss on the insulating member and thereby mounted in a fixed circuit controlling alignment with the other switch part. The insulating member preferably is provided with a pair of openings each extending through one of the bosses so that the insulating member, together with the switch parts mounted thereon, may be fixedly mounted upon a pair of supporting posts or studs projecting from a suitable base or supporting plate. Where it is desired to build up a multiple contact switch, a plurality of the insulating members, each with its own pair of cooperating switch parts mounted thereon, may be slid over the same supporting posts or studs so that all the switch members are mounted in a fixed alignment and clamped between adjacent insulating members. For a cam operated sequence

switch construction, two rows of the aligned switch parts may be mounted in opposition with a rotatable cam shaft extending therebetween so as to sequentially operate the several switches in a desired sequence determined by the cams and the relative location of the switches. This results in a compact, sturdy multiple switch contact structure in which separate terminals for wiring connections to each switch part may be readily provided with each switch part firmly clamped in its operative position by the common clamping means at the end of the supporting posts or studs for all the switch parts. This enables the multi-contact switch structure to be readily assembled or disassembled. Also, since the separate switch parts if desired may be substantially duplicates and likewise the insulating and mounting parts, a sequential control switch mechanism involving a complex sequence of operation may be built up from relatively few and simple parts.

A preferred embodiment of the invention is illustrated in the accompanying drawing in which Fig. 1 is a schematic exploded view of the improved multi-contact sequence switch mechanism of the present invention adapted for use in an oil burner sequencing control with certain parts omitted for the sake of clarity; and Fig. 2 is a perspective assembled view of the multi-contact sequencing switch mechanism illustrated in Fig. 1 showing more in detail how the separate wiring terminals may be provided for each of the several switch parts.

As indicated in Fig. 1, the improved multi-contact sequencing switch mechanism comprises a plurality of stationary switch parts 10, 12, 14 and 16, and a plurality of cooperating movable switch parts 11, 13, 15 and 17, the latter being operated in a desired sequence by means of the cams C₁, C₂, C₃, and C₄ carried on the rotatable shaft 18 operated by the electric timing motor 19 through suitable speed reducing gearing enclosed within casting 20.

The switch stationary part 10 is shown in the form of a plate with a non-circular opening 22 formed therein adapted to fit over the boss or projection 23 formed on the insulating member 24 which preferably is of suitable moulded insulating material. The member 24 is provided with an opening 25 extending through the boss 23 so that the member 24 may be threaded over and supported upon a mounting post 26 extending from the supporting base or plate 27 which carries the cam shaft 18 and the timing motor 19, as more clearly shown in Fig. 2. Also, as indicated in Fig. 2, the other end of the insulating member 24 is provided with a boss similar to boss 23 and an opening similar to opening 25 so that the other end of the insulating member 24 may be threaded over and thereby mounted upon the supporting post 29 extending from the base 27

similarly to the post 26. This enables the supporting plate 31, upon which the movable switch member 11 is mounted, to be threaded over the boss on the lower end of the member 24 and thereby held in a fixed operating relation with the switch part 10.

As indicated in Figs. 1 and 2, the other cooperating pairs of switch parts 12, 13, 14, 15, 16 and 17, together with the special lockout switch parts L₁ and L₂, are similarly mounted in fixed co-operating relation upon similar insulating members 32, 33, 34, and 35, each of which is provided at its opposite ends with a non-circular boss having an opening therethrough so that all the parts may be threaded on the supporting posts 26 and 29 with suitable insulating spacers S₁, S₂, S₃ at the ends, and the nuts 36 and 37 tightened up to clamp all the various switch parts into an integrated unit.

As shown in Fig. 2, and indicated schematically in Fig. 1, a similar series of cooperating switch parts 51, 52, 53, and 54 are assembled in opposing staggered relation upon the insulating members 55, 56, 57, and the studs or mounting posts 40 and 41 which extend from the base 27 on the opposite side of the cam shaft 18, the latter being provided with a suitable series of cams, C₁ to C₉ as indicated in Fig. 1, for operating all the switches.

Thus by means of the improved construction of the present invention, the opposite series of cam operated switches may be clamped in closely aligned relation upon the four studs 26, 29, 40 and 41 which extend in spaced apart relation from the base 27 through the plurality of suitably formed insulating members or blocks each carrying the switch parts so as to electrically insulate them from the studs as well as from each other.

When all of the switch parts are assembled together, each part is held clamped between the adjacent insulating members or blocks. Preferably an end plate 42, provided with a central bearing opening for the end of the cam shaft 18 is provided with suitably spaced openings for receiving the ends of the four supporting studs 26, 29, 40 and 41. Thus by tightening up the nuts on the threaded ends of the studs, the end plate 42 is drawn inwardly so as to clamp all of the insulating blocks together with the switch parts clamped in proper position on their respective bosses between the adjacent insulating blocks.

Each of the switch parts preferably is provided with a suitable wiring terminal, either of the screw clamped type as shown at 43 or of the soldered or welded type shown at 44.

As pointed out in my prior application, the soldered or welded wiring terminal holding means may be used for the permanent connections between the integral parts of the sequencing switch mechanism, while the screw clamp type of wiring terminal holding means provides readily removable connections to the non-integral parts of the burner control system. This facilitates the inter-connection of the control sequence timing switch mechanism with the master control, combustion switch, various operating elements of the burner, and also the power supply means, which have been omitted for the sake of simplicity. The improved construction of the present invention enables all of the high voltage switches of the oil burner control to be located on one side of the cam shaft, while all the low voltage control switches may be located on the other side of the cam shaft.

What I claim as new and desire to secure by Letters Patent of the United States, is:

1. In a control switch mechanism, the combination of supporting means including a pair of spaced apart parallel rods, an insulating member having a pair of spaced apart non-circular bosses with openings extending through said bosses for slidably mounting said member on said rods, a metal plate provided with a non-circular opening for slidably mounting said plate on one of said bosses, a switch contact mounted on one edge of said plate, a separate metal plate provided with a non-circular opening for slidably mounting said plate on the other of said bosses, a movable switch contact resiliently mounted on one edge of said separate plate in circuit controlling relation with said first switch contact, and means including a second insulating member slidably mounted on said rods for clamping said plates on said bosses between said insulating members.
2. In a control switch mechanism, the combination of a base having a pair of spaced apart parallel studs extending therefrom, an insulating member having a pair of non-circular bosses extending in spaced apart parallel alignment therefrom with openings extending through said bosses for slidably mounting said member on said studs, a metal plate provided with wiring terminal holding means and with a non-circular opening for slidably mounting said plate on one of said bosses, a separate metal plate provided with wiring terminal holding means and with a non-circular opening for slidably mounting said plate on the other of said bosses, a switch contact mounted on one edge of said first plate, a cooperating movable switch contact resiliently mounted on one edge of said separate plate in circuit controlling relation with said first switch contact, a second insulating member provided with a pair of spaced apart openings extending therethrough for slidably mounting said member on said studs to hold said plates on said bosses, and means adjacent the ends of said studs for clamping said insulating members together with said plates therebetween.
3. In a control switch mechanism, the combination of a base having opposite pairs of spaced apart parallel studs extending therefrom, a pair of insulating members, each having a pair of non-circular bosses with openings extending through said bosses for slidably mounting said members in opposing relation on said pairs of studs, a pair of metal plates mounted in opposing relation on each of said members with each plate provided with a non-circular opening for slidably mounting said plate on a corresponding one of said bosses thereof, a switch contact mounted on the inside edge of one of each pair of said plates, a movable switch contact resiliently mounted on the inside edge of the other of each pair of said plates in circuit controlling relation with said first switch contact, a cam switch operating member mounted on said base between said pairs of studs and extending between said movable switch contacts for controlling operation thereof, and means including a second pair of insulating members, each slidably mounted on a corresponding pair of said studs, and an end plate slidably mounted on said studs and provided with a bearing for supporting the end of said cam switch operating member for clamping said plates on said bosses between said insulating members.

JOHN EATON.
